UNITED STATES PATENT OFFICE

GASTON DUVAL, OF ROUEN, FRANCE, ASSIGNOR TO ETABLISSEMENTS JEAN SCHWARZE
ET H. MAHE, SOCIETE A RESPONSABILITE LIMITEE, OF PARIS, FRANCE

SIGNALING DEVICE FOR AUTOMOBILES

Application filed February 16, 1928, Serial No. 254,866, and in France February 21, 1927.

My invention relates to signaling devices for indicating the direction in which an automobile is going to turn. Said signaling device is of the type in which the turning signal is given by the display of a two-color arm pivotally mounted and adapted to point transversely in the direction which the vehicle is about to take.

One of the objects of my invention is to provide a signaling device of the character indicated which shall have a minimum number of parts.

To this end the signal arm consists of two segments articulated one upon the other, in a manner to fold up when the arm is in a position of rest and to unfold during pivoting and to remain unfolded during the time that the signal is in action.

A signal arm may thus be employed which is sufficiently large to allow it to be readily seen when it enters into play, but at the same time, occupying but a small space when in a position of rest.

Other objects of the invention will be obvious to those skilled in the art with reference to the accompanying drawings, illustrating two embodiments of my invention, when taken in connection with the present specification of which it forms a part.

80 In the drawings:

Fig. 1 is an elevational view of my device in a position of rest;

Fig. 2 is a side view corresponding to Fig. 1;

85 Fig. 3 is a section along the line 3—3 of Fig. 2;

Fig. 4 is a partial view similar to Fig. 3 illustrating the apparatus in a different position;

90 Fig. 5 is a partial view similar to Fig. 4 illustrating the apparatus in still another position;

Fig. 6 is a front view of a modification; and

95 Fig. 7 is a corresponding side view of Fig. 6.

Referring to the drawings, the mechanism is confined between two plates 1, 1a connected together by means of pillars 2. The 100 signal arm is formed of two parts 3, 3a piv-

oted together at 4. The general form of said arm is that of an arrow. At the end opposite to the pivot 4, the member 3 of the signal arm carries a grooved pulley 5 mounted on a stud 6 carried by plate 1. The said pulley 5 is intended to be operated by a driving cord under the control of the person driving the car. Between the said pulley and the plate 1 is interposed a fixed cam 7 whose form and operation will be subsequently described.

The pivot shaft 4 of the two segments of the signal arm is fixed to the outer segment 3a. It carries on the side of segment 3 toward the plate 1, a small disc 8 with two projecting pins 8a. The distance between said pins corresponds to the thickness of a rod 9, capable of sliding longitudinally with respect to segment 3 in supports 9a fixed to said segment. The rod 9 carries, on the end toward cam 7, a shoe 9b which is maintained in constant contact with said cam by means of a spring 10 surrounding the rod 9. On the other extremity of said rod is formed a double bevel.

The pivot shaft 4 of the two segments of the signal arm extends through the outer segment 3a and carries between said segment and the plate 1a, a toothed disc 11 adapted when the arm turns on stud 6 to 80 mesh with pins 12 fixed for that purpose on the plate 1a. The two diametrically opposite teeth of disc 11 lying in the axis of segment 3a project out further than the others.

On the external face of plate 1a is attached 85 a casing 13 for a small lamp (not shown) said casing being provided with lateral apertures 13a. The upper front part of the lamp casing may be utilized, as shown, for carrying the stop signal. The circuits of the lamps 90 are preferably controlled by the movement of the signal arm.

Operation

When the apparatus is at rest (Figs. 1 to 3), the segment 3 of the signal arm is vertical and the segment 3a folded back thereupon and hangs in front thereof. The whole is concealed behind the plate 1a. If by acting on the control cable the arm 3 is caused to

swing in the direction of the arrow f for example, one of the large teeth of disc 11 comes in contact shortly with one of the pins 12.

The segment 3, continuing to swing, the segment 3a turns about the pivot 4, in the direction of the arrow f^1 , the other teeth of disc 11 coming successively into engagement with the pins 12.

When the segment 3 has reached the position of Fig. 4, the disc 11 which has made a half turn comes to the end of the pins 12 and the segment 3a is then in line with the segment 3. At this moment the shoe 9b of the rod 9, which, up to this moment was in contact with a circular part of the periphery of the cam 7, travels up an inclined surface of said cam, which has for an effect to engage the bevelled extremity of rod 9 between the pins 8a, thus locking together the two sections 3, 3a of the signal arm. Shortly after locking takes place the shoe 9b moves onto another circular part of the periphery of the cam, in such wise that the rod 9 is pushed out and maintained in that position between the pins 8a. The segments 3, 3a then form but a single piece and the signal arm when turned to its extreme position finally stops in the position of Fig. 5 which is its operative position. When the signal arm is moved back to its position of rest, the same effects take place but in the inverse direction.

If instead of causing the signal arm to swing in the direction of the arrow f from its position of rest, it is swung in the opposite direction, the development of the signal arm is effected as before but on the other side of the apparatus whose parts are symmetrically disposed.

As the signal arm is unfolded over and over be it on one side or upon the other it is illuminated at night by the slots 13a of lamp 13.

In the embodiment represented in Figs. 6 and 7, the arm or segment 3 is made in the form of a casing 14 rigid with the pulley 5 which is loosely mounted on a fixed pivot shaft 6. On the shaft 6 is fixed a sprocket wheel 15 which is stationary and around which rolls a chain 16 which meshes with a sprocket wheel 17 of a smaller pitch and diameter than the lower sprocket wheel 15. Said sprocket wheel 17 is fixed on the shaft 4 rigid with the segment or arrow 3a.

Obviously by causing the pulley 5 to turn by means of a suitable cord, the casing 14, as a result, is turned in one direction or the other which determines not only the swinging of the said casing 14 but likewise the rolling of the chain in one direction or the other about the fixed sprocket wheel 15, which produces rotation of sprocket wheel 17 and as a result the development or folding up of the arrow 3a which moves into alignment with the arm 3 (position of Fig. 5 or symmetrical position).

In this embodiment it is unnecessary to supply any such means as above disclosed by reference numerals 7, 8, 9 etc. for maintaining the arrow in its unfolded position, as the chain assures this maintenance without recourse to any intermediate means.

As previously, when the arrow is folded, it disappears completely in the body of the apparatus, that is, at the rear side of the stop signal as shown in Fig. 3 and the arrow being thus invisible, the apparatus viewed from the rear appears as shown in Fig. 1.

The lighting of the arrow in the night may be assured as has already been mentioned by apertures 13a laterally disposed lighted by lamps not illustrated or by a bulb 18 (Fig. 2) whose lighting circuit includes on each side of the socket of the apparatus a contact 19 (Fig. 4) normally open and which is grounded, that is, placed in contact with the socket or other metallic part of the apparatus when the arm or segment 3 has arrived at its extreme position to the right or left (Fig. 5).

While I have shown what I deem to be the preferable forms of my device I do not wish to be limited thereto as various changes may be made in the details of construction and the arrangement of parts without departing from the spirit of the invention comprehended within the scope of the appended claim. In particular the unfolding of the arm might readily take place by means of a series of pinions meshing with a toothed centrally disposed sector fixed to the frame.

Having thus described my invention what I claim as new and desire to secure by Letters Patent is:

A direction signaling device for automobiles comprising a casing having an opening on each side, a two part folding arm for signaling pivotally mounted and normally occupying a folded position within said casing invisible from without, said arm being arranged to turn on its pivot in both directions for display through either of said openings, a stationary sprocket wheel mounted on said pivot, another sprocket wheel integral with the outer part of the arm and mounted at the point of articulation of both parts, and a continuous chain passing on both sprocket wheels, whereby the rotation of the arm on its pivot automatically causes the two parts of said arm to unfold and to maintain a position of alignment when said arm is swung in either direction.

In testimony whereof I have signed this specification.

GASTON DUVAL.
